UNITED STATES PATENT OFFICE.

ALBERT V. TODD, OF OELWEIN, IOWA.

BURGLAR-ALARM.

SPECIFICATION forming part of Letters Patent No. 605,589, dated June 14, 1898.

Application filed October 4, 1897. Serial No. 653,966. (No model.)

To all whom it may concern:

Be it known that I, ALBERT V. TODD, a citizen of the United States, residing at Oelwein, in the county of Fayette and State of Iowa, have invented a new and useful Burglar-Alarm, of which the following is a specification.

My invention relates to improvements in burglar-alarms of that class to be applied to a door and adapted for operation automatically to explode a cap or cartridge when the door is opened or tampered with.

The object I have in view is to provide a simple and cheap device which may be easily applied to a door and which has its elements so constructed and arranged as to serve in a twofold capacity—first, as a means for exploding a cap or cartridge; and, secondly, as a device for locking the door after the cap or cartridge shall have been exploded on the initial opening of the door.

My improved device also serves as a fastener for holding the door in an open or partially open position, and the parts of the device are constructed in a novel manner to enable the bolt or plunger to be readily adjusted by hand, either when the device is used as a door-fastener or as a burglar-alarm.

With these ends in view the invention consists in the combination of elements and in the construction and arrangement of parts, as will be hereinafter fully described and claimed.

To enable others to understand the invention, I have illustrated the preferred embodiment thereof in the accompanying drawings, forming a part of this specification, and in which—

Figure 1 is a perspective view showing my improvement applied to a door. Fig. 2 is a vertical sectional elevation through the fastener and alarm, showing the bolt or plunger lowered into position to serve as a means for holding the door in its opened or partially opened condition. Fig. 3 is a plan view of the bolt or plunger adjusted in position to serve as a means for exploding a cap or cartridge. Fig. 4 is a perspective view of the device detached from the door and looking at the inner chambered side of the casing.

Like numerals of reference denote corre-

sponding parts in all the figures of the drawings.

1 designates the casing, and 2 is the bolt or plunger, which is loosely fitted in the casing 55 to slide therein and to be capable of having turning movement or adjustment, so that the bolt may be adjusted to serve as a means for exploding a cap or as a fastening device for holding the door in its opened or partially opened condition.

The casing 1 is constructed in a compact manner to contain the bolt or plunger, its impelling spring, and one or more caps or cartridges. This casing is provided with a longitudinal chamber or cavity 3, which opens through the inner or rear side of said casing. The lower end of the casing is solid, except for the vertical aperture 4, and the upper end of the casing is also solid and forms an integral part of said casing, except for the aperture 5 and the keeper-slot 6. The apertures 4, 5 are in vertical alinement with each other and they open into the chamber or cavity 3, and the keeper-slot 6 is formed longitudinally 75 in the upper front part of the casing 1, so as to open through the front side and upper end of said casing, the inner edge of the keeper-slot being in communication with the upper aperture 5 in said casing. The casing is further 80 more provided with a series of integral apertured lugs 7, which extend beyond the casing and furnish a convenient means for the attachment of the device to the door by means of screws, which may pass through said apertured 85 lugs and into the door. Said casing is also provided with the rest-posts 8, which extend upwardly from an enlarged upper end or head of the casing 1, and said rest-posts are disposed on opposite sides of the keeper-slot 6, 90 the inner edges of the rest-posts 8 being curved or beveled for the purpose of free movement or passage of the head of the locking bolt or plunger when the device is to be used as a burglar-alarm. Near the rear side 95 of the enlarged head of the casing is provided the guide pins or studs 9, each of said pins being arranged in close parallel relation to one of the rest-posts and forming therewith a guide space or throat, through which the head 100 of the bolt or plunger may pass and by which the striker-hammer on said bolt or plunger is

directed with precision and certainty upon the cap or cartridge placed on the head of the casing 1. This head of the casing is furthermore provided with sockets 10, one of which is situated adjacent to the throat formed by and between the guide-pin and the rest-post. This socket is of suitable depth to contain a cap or cartridge, and said cap or cartridge is adapted to fit snugly in said socket 10 to be held steadily and firmly in place thereby and in the path of the striker-hammer on the bolt or plunger. It is evident that the cap or cartridge may be readily fitted in place in the socket, and after it shall have been exploded 15 the shell or fragment may be readily detached from the socket and a new cap or cartridge placed in the latter. If desired, I may provide the casing with a single socket, rest-post, and guide-pin; but I prefer to duplicate these 20 parts and to arrange them on the casing on opposite sides of the keeper-slot 6 for the purpose of adjusting the bolt or plunger to engage with either post and enable the lock and alarm to be used on right or left doors, as 25 may be desired.

The bolt or plunger 2 consists of a straight rod or length of wire or bar metal, one end of which is bent at an angle to form the head 2^a, the straight shank of the bolt or plunger 30 passing through the guide-aperture 4 and the chamber 3 of the casing, and the lower end of said bolt or plunger is hollow to form a seat 12. In this seat is fitted a foot 13, which may consist of a piece of rubber or 35 other suitable friction material, and which is fastened to the bolt or plunger by cement or in any other suitable way. The friction-foot 13 of the bolt or plunger is adapted to engage with the floor for the purpose of holding 40 the door in its opened or partially-opened position.

Within the chamber or cavity 3 of the casing 1 is arranged a coil impelling-spring 14, which encircles the bolt or plunger 2, so as to be 45 held in position thereby, and one end of this impelling-spring is seated against the closed upper end of the casing 1, while the other end of said spring fits against a washer 15, the latter being held against sliding movement on the bolt or plunger by a transverse removable pin 16, attached in a suitable way to the plunger or bolt. This coiled spring is 50 quite strong in order to impel the plunger forcibly in a downward direction, and the spring thus serves to press the foot 13 firmly against the floor when the device is used as a door-fastener, and also to impart a quick strong play to the bolt or plunger in order that the 55 striker-hammer of the bolt may be brought 60 with sufficient force against the cap or cartridge to explode the latter when the device is used as a burglar-alarm. The head 2^a of the bolt or plunger is of sufficient length to extend beyond the rest-post 8, on which it 65 may be adjusted when the device is used as a burglar-alarm, and in the path of this projecting end of the bolt-head is arranged a

stop or detent 17. This stop or detent is shown in the drawings as consisting of a staple having an offset-head, and this staple is fastened to the door-jamb, so as to have its offset lie in the path of the protruding end of the head of the bolt, whereby as the door is opened the head 2^a of the bolt is brought into engagement with the offset of the stop or detent, and the bolt is thus turned to a position where it will pass between the rest-post and the guide-pin for the striker-hammer on said bolt-head to impinge against the cap or cartridge in the socket 10 of the casing. The 75 angular bolt-head 2^a is provided at a point intermediate of its length with a striker-hammer 18, said hammer being made as an integral part of the bolt or plunger, or it may be fastened rigidly to the head 2^a thereof. 85

In using my device as a burglar-alarm and door-fastener I provide a socket 19 on the floor, said socket lying in the path of the lower end or foot of the bolt and at a short distance in rear of the door, so that the foot 90 of the bolt may enter the socket after the bolt has been shot to explode the cartridge when the door is surreptitiously opened.

The operation of my invention may be described briefly as follows: The casing 1 is applied to the door near its lower free edge by passing suitable screws through the apertured lugs of said casing, thus fastening the device firmly in place on the door. When the door is opened or partially opened, the bolt may 95 be turned in the casing for its angular head 2^a to enter and slide in the keeper-slot 6, and the foot of the bolt is thus projected a sufficient distance below the door for said foot 13 to engage firmly with the floor and hold the 100 door in its opened position. To use the device as a burglar-alarm, a cap or cartridge 11 is placed in one of the sockets 10 of the casing, and the bolt is lifted and turned for the 105 angular head 2^a to rest upon one of the rest-posts 8 and to have its free end projected beyond one side of the casing. The door being 110 closed, the stop or detent 17 is fastened to the door-jamb in a position for the offset of said detent to be in the path of the free protruding end of the bolt-head. Should an attempt be made to open the door, the device 115 will be carried with the door toward the offset of the detent, and a continued movement of the door will turn the bolt or plunger to a 120 position where the striker-hammer is brought over and in line with the cap or cartridge 11, because the protruding end of the head 2^a engages with the offset in the detent 17. The 125 head of the bolt being freed from engagement with the rest-post, the spring reacts and impels the bolt forcibly in the direction of its length, thus bringing the striker-hammer of the bolt-head into forcible contact with the cap or cartridge and exploding the latter to 130 give the alarm.

From the foregoing description, taken in connection with the drawings, it will be seen that I have provided an extremely simple and

efficient device especially adapted to serve the purposes of a door-fastener to hold the door in its open position and as a burglar-alarm, that the device may be easily and 5 readily adjusted to fulfil either of these functions, and that the device may be easily and quickly applied to a door.

The socket 19 on the floor may be provided by forming a hole in the floor or by using an 10 apertured plate, which may be fastened to the floor, and this socketed plate is arranged for the foot of the bolt to engage therewith after the bolt has been shot and the cartridge exploded, thus furnishing a means for locking 15 the door after the alarm has been given.

I am aware that changes in the form and proportion of parts and the details of construction may be made by a skilled mechanic without departing from the spirit or sacrificing 20 any of the advantages of the invention. I therefore reserve the right to make such modifications and alterations as clearly fall within the scope of the invention.

Having thus described the invention, what 25 I claim is—

1. In a combined burglar-alarm and door-fastener, a casing provided with a keeper-slot, a cartridge-socket out of line with said slot and an elevated rest-post adjacent to said 30 socket, in combination with a spring-controlled bolt fitted in the casing to slide and turn therein, said bolt provided with an angular head adapted to fit in the keeper-slot and enable the foot of the bolt to be projected 35 sufficiently beyond the casing to engage with the floor, and also adapted, when the bolt is turned in one direction, to engage with the rest-post and sustain the bolt in a raised position, and means to turn the bolt and move 40 the striker-hammer on the bolt-head into alignment with the cartridge-socket, substantially as and for the purposes described.

2. In a combined burglar-alarm and door-fastener, a casing provided in its head with 45 a cartridge-socket, the parallel rest-post and guide-pin adjacent to said socket, and a longitudinal keeper-slot, combined with a spring-

controlled bolt provided with an angular head and arranged to project below the casing, a friction-foot carried by the lower end of the bolt, and a striker-hammer carried by said head of the bolt, substantially as described for the purposes set forth. 50

3. In a combined burglar-alarm and door-fastener, a casing provided with an enlarged head, a central keeper-slot, cartridge-sockets in the head and on opposite sides of the keeper-slot, rest-posts adjacent to the cartridge-sockets and on opposite sides of said keeper-head, and guide pins or studs parallel 60 to the rest-posts, in combination with a spring-controlled bolt fitted loosely in said casing to slide and turn therein and provided with an angular head adapted to project beyond either of said rest-posts when the bolt is raised for 65 said head to engage with the rest-post, a striker-hammer carried by the bolt-head, and a detent in the path of said angular bolt-head, substantially as described for the purposes set forth. 70

4. The combination of a casing provided with a keeper-slot which extends below an enlarged head of said casing and with a cartridge-socket in said enlarged head, a spring-controlled bolt carrying at its upper end a 75 striker-hammer, a friction-foot attached to the lower end of said bolt and an elevated rest-post supported by the casing at one side of the keeper-slot and adjacent to the cartridge-socket, whereby said bolt may be fitted 80 in the keeper-slot and projected sufficiently beyond the casing for the friction-foot on said bolt to engage with the floor, or said bolt may be raised to engage with the rest-post and be held in position for the striker-hammer to enter the cartridge-socket, substantially as described for the purposes set forth. 85

In testimony that I claim the foregoing as my own I have hereto affixed my signature in the presence of two witnesses.

ALBERT V. TODD.
